C. M. COTT,

LOOSE LEAF BINDER.

APPLICATION FILED AUG. 5, 1916

1,229,891.

Patented June 12, 1917.

Charles M. Cott

By Shepherd Campbell

The Attorney's

UNITED STATES PATENT OFFICE.

CHARLES M. COTT, OF COLUMBUS, OHIO.

LOOSE-LEAF BINDER.

1,229,891.

Specification of Letters Patent. Patented June 12, 1917.

Application filed August 5, 1916. Serial No. 113,286.

To all whom it may concern:

Be it known that I, CHARLES M. COTT, a citizen of the United States, residing at Columbus, in the county of Franklin and State 5 of Ohio, have invented certain new and useful Improvements in Loose-Leaf Binders, of which the following is a specification.

This invention relates to loose-leaf binders, particularly adapted for use in public 10 offices in connection with the recording of deeds, mortgages, court-orders, probate records, etc., though of course it is adapted for use in other relations. It is desirable, in the construction of loose-leaf binders of this nature, to provide a structure which will be 15 simple in form, economical to manufacture, and one in which the individual retaining posts may be independently released. It is also desirable to provide a structure constructed in such manner that the individual 20 traversing elements of the post will be securely held against accidental displacement and loss and in which the traversing element may be permanently locked against removal after the book has been filled and it is 25 no longer desired to make changes therein.

The present construction accomplishes all of the foregoing objects in a simple, economical and efficient way.

30 Further objects and advantages of the invention will be set forth in the detailed description which now follows.

In the accompanying drawing:

Figure 1 is a vertical sectional view 35 through the rear portion of a loose-leaf binder showing the parts in assembled relation.

Fig. 2 is a plan view of one of the "metals" hereinafter described.

40 Fig. 3 is an edge view of the structure shown in Fig. 2.

Fig. 4 is a detail perspective view of one of the retaining wires hereinafter described, and

45 Fig. 5 is a partial under-side perspective view of one of said metals.

Like numerals designate corresponding parts in all of the figures of the drawing.

Referring to the drawing 5 and 6 designate the covers and 7 designates the uniting back of a loose - leaf binder such as is

commonly employed for public records. It is usual in such structures to provide posts 8 which extend through the leaves 9 of the volume and bind said leaves together. In 55 carrying out the invention, I provide the duplicate metals 10 and 11 which are fixedly attached to the backs 5 and 6. These metals are bent along their projecting edges to form elongated, box-like housings 12 and 13. The front edges of these housings are cut out or notched as at 14 to receive the ends of the posts 8. For each end of each of the posts, there is provided one of the retaining members illustrated in Fig. 4, these 65 retaining members comprising a wire bent to U shape to thereby provide a post engaging arm 15 and a locking arm 16. The bight portions of the retaining members constitute finger grasps 17. The finger grasps of 70 the two outer retaining members are knurled or roughened while the finger grasps of the inner retaining elements are bent slightly out of the plane of the body portions thereof to facilitate the ready grasping of the 75 same. The inner ends of the arms 16 are provided with transversely extending lugs 18 which, when these retaining elements are in place, project through recesses 19 formed in the rear walls 20 of their respective housing. These rear walls 20 are also provided with notches 21 for the reception of the 80 locking projections 18.

When the parts are in the position illustrated in Fig. 1, the free ends of the arms 15 85 project through the usual perforations 22 formed in the ends of the posts 8. The movement of the individual retaining members to this locking position, is limited by the projections 18 engaging the ends of the 90 recesses 19. The outward movement of the individual retaining element is likewise limited by the length of the slot 19, it being apparent that the transverse projection 18 will prevent the complete withdrawal of the 95 retaining element and will thereby prevent its accidental dislodgment or loss as well as maintain them always in convenient position whereby a very slight inward movement will bring them to locking and post retaining position.

After the book has been completed, it is

desired to permanently lock it against the removal of any of the sheets therefrom or the addition of any sheets thereto. By inserting a pointed instrument through the opening 23, the locking arm 16 may be sprung sufficiently to withdraw the transverse projection 18 from the notch 19 and the individual retaining elements may be pushed further into the housing, until the 5 finger grasps 17 lie entirely within the housing and until the transverse projections 18 snap into the openings or notches 21 formed in the rear walls 20 of the respective housings. In order to do this I bend the finger 10 grasps of the inner retaining elements into the plane of the remainder of said elements. This movement of the finger grasps into the housings and the engagement of projections 18 in notches 21 results in permanently locking 15 the parts so that no leaves may be added to or removed from the volume, thereafter.

It has been found that the leaves at the rear outer corners of the body of leaves 9 frequently become mutilated, said leaves 20 tending to curl outwardly, and to render it difficult to properly position the parts when new leaves are to be added or leaves are to be removed from the volume. To maintain the leaves in proper shape at this point, I 25 provide thin metallic plates 24, said plates being preferably provided with down turned flanges 25 which engage behind the rear edges of the leaves, said plates likewise being provided with slightly down turned 30 flanges 26 at their front edges, but this latter is not necessary.

It will be noted that the housings 20 are cut away centrally of the metals to provide a recess 27. This provides a space in which 35 the finger grasps 17 of the two inner retaining elements may move. Important advantages are derived from providing an individual retaining element for each of the posts and it is to be noted that in the present construction, the two inner retaining elements move outwardly to locking position while the two outer retaining elements move inwardly to locking position. By providing these individual retaining elements, 40 I am enabled to release some of the posts without releasing others. Much difficulty has been experienced heretofore in inserting new leaves in binders of this character due to the fact that it has been customary to 45 simultaneously release all of the posts and to remove from said posts the leaves that are above the point where the new leaves are to be inserted, leaving all of the posts projecting through the remaining leaves. The 50 leaves removed become disarranged and the openings therein get out of alinement making it difficult to replace the leaves and necessitating the exercise of great care in doing so.

By virtue of the present construction, I 65 am enabled to avoid this difficulty as follows: I release all of the posts at one side of the volume, then I pass through two of the posts, say the two outer posts, small retaining rods corresponding to the arm 15. Then 70 I release the outer posts only, at the opposite side of the volume and remove the leaves that it is desired to remove along with the outer posts. These outer posts projecting through the removed leaves maintain them 75 in proper alinement and render their replacement very easy. The inner posts, in the meantime, remain in their normal position and maintain in alinement the leaves that are not removed from the volume. 80

It is to be understood that the invention is not limited to the precise construction set forth. While the particular form of retaining element shown in Fig. 4 may be very economically manufactured and while it 85 will serve the purposes set forth with efficiency, it is apparent that the particular form of retaining element may be varied without departing from the idea herein involved of providing individual retaining 90 elements for the separate posts or from the further idea of having some of these individual retaining elements operable from a point at the middle of the volume and others of said elements operable from the ends of 95 the metal. Furthermore, the locking mechanism and likewise the releasing means may be varied without departure from the invention, it being understood that the invention covers such modifications as fairly come 100 within the spirit as well as the terms of the appended claims.

Having described my invention, what I claim is:

1. A loose leaf binder comprising a plurality of leaf retaining posts, a metal carried by the cover and an individual retaining element for each of the posts movably supported upon said metal, one of said retaining elements being arranged to engage 110 its respective post upon inward movement of said element and another of said elements being arranged to engage its post upon outward movement thereof.

2. A loose leaf binder comprising a plurality of leaf retaining posts, a metal carried by the cover and an individual retaining element for each of the posts movably supported upon said metal, some of said retaining elements having finger grasps disposed at the outer ends of the metal and others of said retaining elements having finger grasps disposed toward the central portion of the metal.

3. A loose leaf binder comprising a plurality of leaf retaining posts, a pair of covers adapted to be united by said posts, a metal carried by each of the covers and a

- plurality of individual retaining elements for the posts, said retaining elements being slidably mounted upon the metals, and interengaging means between the retaining elements and metals for limiting the movement of the retaining elements to a position wherein they are released from the posts, said metals being also provided with means for engaging said retaining elements and 5 operable when said retaining elements have been moved to an inaccessible position upon the metals and serving to lock said retaining elements permanently in a post engaging position.
- 10 4. A loose leaf binder comprising a pair of covers, a plurality of leaf retaining posts uniting said covers, a metallic housing carried by each of the covers and a plurality of post retaining elements slidably disposed in 15 said housing, each of said post retaining elements comprising a post traversing arm and a locking member, and the housing being formed to be engaged by said locking member.
- 20 5. A loose leaf binder comprising a pair of covers, a plurality of leaf retaining posts uniting said covers, a metallic housing carried by each of the covers and a plurality of post retaining elements slidably disposed in 25 said housing, each of said post retaining elements comprising a post traversing arm and a locking member, and the housing being formed to be engaged by said locking member, said means being operable when the retaining elements have been moved to an inaccessible position within the housing, to 30 lock said elements against movement and in a post engaging position.
- 35 6. A loose leaf binder comprising a pair of covers, a plurality of leaf retaining posts uniting said covers, a metallic housing carried by each of the covers and a plurality of post retaining elements slidably disposed in 40 said housing, each of said post retaining elements comprising a post traversing arm and a locking member, and the housing being formed to be engaged by said locking member, some of said retaining elements being 45 movable inwardly from the outer ends of the housing and others of said retaining elements being movable outwardly from an intermediate point of the housing when being moved to post engaging position.
- 50 7. A loose leaf binder comprising a pair of covers and a plurality of leaf retaining posts for uniting said covers, a metal carried by each of said covers and bent to form a housing extending along the edge of said cover and a plurality of individual retaining elements for the posts slidable in said housing, each of said elements being formed of wire bent to a shape to constitute a post traversing arm and a yieldable locking arm.
- 55 8. A loose leaf binder comprising a pair of covers and a plurality of leaf retaining posts, a metal carried by each of said covers and bent to form a housing extending along the edge of said cover and a plurality of individual retaining elements for the posts slidable in said housing, each of said elements being formed of wire bent to a shape to constitute a post traversing arm and a yieldable locking arm, the uniting bight portions between said arms constituting finger grasps which normally 60 project from the housing.
- 65 9. A loose leaf binder comprising a pair of covers, a plurality of leaf retaining posts for uniting said covers, a metal bent to form a housing carried by each of said covers, said housing being cut away at intervals for the reception of the ends of the posts and said housing being additionally cut away at a point intermediate its ends, and a plurality of post retaining elements slidable in 70 the housing, some of which are manually operable from the last named cut away portion of the housing and some of which are manually operable from the outer ends of the housing.
- 75 10. In a loose leaf binder the combination with a metallic plate bent to form a housing along its edge and having a cut away portion, of a leaf retaining post adapted to enter said cut away portion and a post retaining element slidable in said housing and formed of a resilient rod or wire bent to 80 form two substantially parallel arms, one of which is shaped to engage the post and unite it to the housing and the other of which is shaped to form a locking member, and the housing being formed to be engaged by said locking member at such a point that when the locking member engages the housing the post retaining element lies in an inaccessible 85 position within the housing.
- 90 11. In a loose leaf binder the combination with a metal bent to form a housing along its edge, said housing having a cut away portion, a leaf retaining post adapted to enter said cut away portion and a resilient post engaging element slidable in said housing and having a portion adapted to traverse said post and a laterally extending member, said housing having a slot formed 95 in its wall within which said laterally extending member travels, and an additional slot with which said laterally extending member engages when the retaining element has been moved to an inaccessible position 100 within the housing.
- 105 12. In a loose leaf binder the combination with a metal bent to form a housing along its edge, said housing having a cut away portion, a leaf retaining post adapted to 110 enter said cut away portion and a resilient post engaging element slidable in said housing and having a portion adapted to traverse 115 said post and a laterally extending member, said housing having a slot formed in its wall within which said laterally extending member travels, and an additional slot with which said laterally extending member engages when the retaining element has been moved to an inaccessible position 120 within the housing.
- 125 13. In a loose leaf binder the combination with a metal bent to form a housing along its edge, said housing having a cut away portion, a leaf retaining post adapted to enter said cut away portion and a resilient post engaging element slidable in said housing and having a portion adapted to 130 traverse said post and a laterally extending member, said housing having a slot formed in its wall within which said laterally extending member travels, and an additional slot with which said laterally extending member engages when the retaining element has been moved to an inaccessible position within the housing.

erse said post and a laterally extending member, said housing having a slot formed in its wall within which said laterally extending member travels and an additional slot with which said laterally extending member engages when the retaining element has been moved to an inaccessible position

within the housing, the housing being provided with an opening through which the release of said laterally extending member 10 from the first named slot may be effected.

In testimony whereof I affix my signature.

CHARLES M. COTT.
